Attorney

UNITED STATES PATENT OFFICE

LLOYD A. DERBY, OF ADRIAN, MICHIGAN

AIR-HEATING APPLIANCE

Application filed January 2, 1929. Serial No. 329,906.

This invention relates to air heating appliances, and more particularly to an apparatus of this character providing a convenient source of heated air under pressure which is portable and accordingly may be employed 5 to great advantage in garages, in thawing frozen pipes or melting grease in transmissions, differentials, joints or the like to render the same fluid and enable its ready removal.

An important object of the invention is to 10 produce a device of this character which may be readily and cheaply manufactured, which will be durable and efficient in service and a general improvement in the art.

These and other objects I attain by the construction shown in the accompanying drawings, wherein for the purpose of illustration is shown a preferred embodiment of my invention and wherein:—

Figure 1 is an end elevation of a heater 20 constructed in accordance with my invention;

Figure 2 is a section on the line 2—2 of Figure 1;

Figure 3 is a fragmentary section at right angles to the view of Figure 2.

Referring now more particularly to the drawings, the heater comprises a cylindrical casing 10 having its ends closed by heads 11 and 12. The casing 10 comprises inner and 30 outer metallic wall elements 13 and 14 having disposed therebetween an insulating lining, such as asbestos 15. Each head 11 and 12 is provided at one side with an ear 16 terminating in spaced relation to the wall of the 35 cylinder and each head has a socket 17 receiving the ends of the wall of the cylinder.

Within each socket 17 is disposed an asbestos pad 18, the pad of the head 11 being held in position by engagement of the end 40 of the casing wall therewith and the pad of the head 12 being secured in position thereon by a socket 19 seated upon the inner face thereof and secured to the head by contact bolts 20 which are extended through and 45 bushed from the head. The head 12 has a flange 21 in surrounding relation to these contact bolts and upon the free edge of this flange is seated a closure plate 22 apertured for the passage of a lead cord 23. The heads 50 are connected to one another to clamp upon

the ends of the casing by means of stay bolts 24, one of which passes through the free ends of the ears 16 and intermediate these ears has mounted thereon a handle 27 by means of which the casing may be manipulated.

The head 11 has an outlet opening 28 in 55 which is mounted a nozzle 29 while the head 12 has an inlet opening 30 with which is engaged a control valve 31 for controlling the supply to the heating chamber 32 formed by the combination of the casing and heads. 60

The outlet 28 and inlet 30 are arranged at opposite sides of their respective heads, so that air passing from the inlet to the outlet must pass over a heating element 33 disposed within the chamber and mounted within the socket. This heating element may be 65 any of the electric resistance units now commonly sold upon the market.

In the use of the device, the air passing 70 through the chamber is considerably heated, and this heating blast directed upon congealed grease both softens the same and tends to separate it from the surface upon which it is applied. This renders the device particularly applicable in cleaning exposed surfaces prior to regreasing or repairing the same. In draining a transmission or differential, the nozzle may be inserted in the filling opening thereof after removing the drain plug and the incoming heated air will 75 serve to liquefy the grease, tending to permit it to flow while the jet of air will assist in forcing the softened lubricant from the case.

Since the construction hereinbefore set forth is capable of a certain range of change 80 and modification without materially departing from the spirit of the invention, I do not limit myself to such specific structure except as hereinafter claimed.

I claim:—

1. In combination, a casing having a cylindrical wall and heads abutting opposite ends of said wall to close the same, said heads being each provided with outstanding ears, stay bolts connecting the heads, one of said stay bolts being passed through the ears, a handle surrounding said stay bolt between the ears, a heating element arranged within the casing, a nozzle communicating with one end of 100

the casing, and means for introducing air under pressure to the casing to the opposite end thereof.

2. In combination, a casing having a cylindrical wall and heads abutting opposite ends of said wall to close the same, said heads being each provided with outstanding ears, stay bolts connecting the heads, one of said stay bolts being passed through the ears, a handle surrounding said stay bolt between the ears, a heating element arranged within the casing, a nozzle communicating with one end of the casing, means for introducing air under pressure to the casing to the opposite end thereof, said heads having sockets receiving the ends of the cylindrical wall, and heat insulating pads disposed within said sockets and retained in position therein by said cylindrical wall.

3. In combination, a casing having a cylindrical wall and heads abutting opposite ends of said wall to close the same, said heads being each provided with outstanding ears, stay bolts connecting the heads, one of said stay bolts being passed through the ears, a handle surrounding said stay bolt between the ears, a heating element arranged within the casing, a nozzle communicating with one end of the casing, and means for introducing air under pressure to the casing to the opposite end thereof, said cylindrical wall comprising inner and outer metallic shells and an interposed heat insulation.

4. In combination, a casing having a cylindrical wall and heads abutting opposite ends of said wall to close the same, said heads being each provided with outstanding ears, stay bolts connecting the heads, one of said stay bolts being passed through the ears, a handle surrounding said stay bolt between the ears, a heating element arranged within the casing, a nozzle communicating with one end of the casing, means for introducing air under pressure to the casing to the opposite end thereof, said heads having sockets receiving the ends of the cylindrical wall, and heat insulating pads disposed within said sockets and retained in position therein by said cylindrical wall, said cylindrical wall comprising inner and outer metallic shells and an interposed heat insulation.

5. An air heating apparatus comprising a portable casing having a head provided with an inlet and a head provided with an outlet, an electrical heating element within the casing, a support for said element, bolts securing the support to one of said heads, the bolts passing through the head and connected to the heating element, a flange carried by said head in surrounding relation to the outer ends of the bolts, and an apertured closure plate secured to the flange.

In testimony whereof I hereunto affix my signature.
